UNITED STATES PATENT OFFICE

159,096

OYSTER OPENING APPARATUS

John L. Plock, Southold, N. Y.

Application December 9, 1948, Serial No. 150,052

Term of patent 14 years

(Cl. D11--1)

To all whom it may concern:

Be it known that I, John L. Plock, a citizen of the United States of America, residing at Southold, Suffolk County, State of New York, have invented a new, original, and ornamental Design for an Oyster Opening Apparatus, of which the following is a specification, reference being had to the accompanying drawing, forming part thereof.

In the drawing,

Fig. 1 is a perspective view of an oyster opening apparatus, embodying my new design.

Fig. 2 is a side view showing the design.

Fig. 3 is an end view showing the design.

I claim:

The ornamental design for an oyster opening apparatus, as shown.

JOHN L. PLOCK.
